UNITED STATES PATENT OFFICE.

JOHN ROBERT CARTER, OF TORONTO, ONTARIO, CANADA.

HEATING DEVICE FOR BATHS AND THE LIKE.

1,074,694.

Specification of Letters Patent.

Patented Oct. 7, 1913.

Application filed November 25, 1912. Serial No. 733,362.

To all whom it may concern:

Be it known that I, JOHN ROBERT CARTER, of the city of Toronto, in the county of York, in the Province of Ontario, Canada, have 5 invented certain new and useful Improvements in Heating Devices for Baths and the like, of which the following is the specification.

My invention relates to improvements in 10 heating devices for baths and the object of the invention is to devise means for heating the upper portion of the bath to a comfortable temperature so as not to unduly shock the body of the user when brought into contact therewith and it consists essentially of 15 means for circulating water at a suitable temperature over the outer surface of the bath around the top edge thereof from a suitable source of supply, to a suitable inlet 20 as hereinafter more particularly explained by the following specification.

Figure 1, is a perspective view of a bath showing my device applied thereto. Fig. 2, is an end elevation of a bath partially in 25 section.

In the drawings like letters of reference indicate corresponding parts in each figure.

A is a bath.

A' is the hot water pipe provided with 30 the usual tap A² and spout A³.

A⁴ is the cold water pipe provided with the usual tap A⁵ and spout A⁶.

B is a branch pipe leading from the pipe A'.

B' is a branch pipe leading from the pipe A⁴.

C is a pipe leading from the branch pipes B and B' and extending upwardly preferably beneath the roll A⁷ formed around the 40 upper edge of the bath. The pipe C extends completely around the bath to the opposite side and B² is an inlet opening communicating with the bath and into which the outlet end of the pipe C extends.

D is a valve located in the branch pipe B and D' is a valve located in the branch pipe B'.

E is the waste pipe of the bath.

E' is a branch pipe connecting the waste pipe to the pipe C.

E² is a valve designed to direct the water through the inlet B² or through the branch pipe E' to the waste pipe E.

Having described the principal parts involved in my invention I will briefly describe the operation of the same.

When a bather desires to fill the bath with water he first turns on the tap D allowing the water to pass from the hot water pipe A' through the pipe C to the inlet B² leading 60 to the bath. If the upper edge of the bath formed by the roll A⁷ becomes too hot the heat may be tempered by turning on the tap D' so as to allow cold water to flow from the pipe A⁴ into the pipe C to mix with the 65 hot water therein until the required temperature is obtained comfortable to the bather. When this is attained the taps D and D' may be turned off and the ordinary taps A² and A⁵ may be turned on as desired 70 to fill the bath. If desired the water may be carried directly to the waste pipe instead of into the bath.

From this description it will be seen that I have devised a very simple means whereby 75 the upper portion of the bath may be rendered comfortable to the bather, should such portion of the bath come in contact with the body of the bather.

What I claim as my invention is— 80

1. In a heating device for baths, the combination with a bath having hot and cold water supply pipes and a waste pipe, of a circulating pipe extending around the bath and terminating in an inlet, branch pipes 85 connecting said circulating pipe with said hot and cold water supply pipe, and connecting said circulating pipe with said waste pipe, valves for regulating the flow and temperature of the water through the circulating pipe, and means for directing such flow into the bath or to said waste pipe.

2. In a heating device for baths and the like, the combination with the bath having a suitable inlet opening, of a water supply 95 device, of a pipe leading from the water

supply device around the bath to the inlet opening, a waste pipe and a controlling valve designed to control the admission of water from the circulating pipe to the waste pipe and the interior of the bath.

3. In a heating device for baths and the like, the combination with a bath and the hot and cold water supply pipes and waste pipe, of a duct leading around the rim of the bath, separate branch pipes communi-

cating between the hot and cold water supply pipes and the duct and separate controlling valves for the branch pipes designed to regulate the proportionate flow of water through such branch pipes to the surrounding duct, as and for the purpose specified.

JOHN ROBERT CARTER.
